UNITED STATES PATENT OFFICE.

JAMES McNAMARA, OF BROOKLYN, NEW YORK, ASSIGNOR TO MERGENTHALER LINOTYPE COMPANY, A CORPORATION OF NEW YORK.

TYPGRAPHICAL MACHINE.

1,076,140.

Specification of Letters Patent. Patented Oct. 21, 1913.

Application filed June 5, 1912. Serial No. 701,760.

To all whom it may concern:

Be it known that I, JAMES McNAMARA, a citizen of the United States, and a resident of the borough of Brooklyn, county of 5 Kings, and State of New York, have invented a new and useful Improvement in Typographical Machines, of which the following is a specification.

My invention relates to typographical machines, such as linotype machines of the 10 general organization set forth in Letters Patent of the United States to O. Mergenthaler, No. 436,532, wherein circulating matrices are released from a magazine in 15 the order in which their characters are to appear in print, and then assembled in line together with spacers, the composed line transferred to the face of a mold, the mold filled with molten metal to form a slug or 20 linotype against the matrices which produce the type characters thereon, and the matrices thereafter elevated and returned through a distributing mechanism to the magazine from which they started.

More particularly it has reference to the 25 means whereby the matrices and spacers are assembled in line, and is designed to accomplish several novel and important results, such as the acceleration of the released type 30 or matrices during or before their passage to the assembling means, the deflection of the type or matrices edgewise into a different plane wherein the spacers are delivered, and finally the advance of the line during 35 composition by means which are controlled as to their actuation by the delivery of the type or matrices thereto.

In the accompanying drawing, I have shown my improved devices in preferred 40 form and by way of example, and as applied to a specific type of machine, but obviously many variations and modifications may be made therein, and in their mode of application, and still be comprised within 45 the scope of my invention. Generally speaking, I desire it to be distinctly understood that I do not limit myself to any specific form or embodiment except in so far as such limitations are specified in the 50 claims.

The drawing is a front perspective view 55 of a portion of a linotype machine, part broken away, and having my invention applied thereto.

The type or matrices are stored in the

channeled magazine B, and their release is effected by the manipulation of the keyboard A, which acts through the reeds A² upon the escapements A³. The released type or matrices then pass downward 60 through the channeled front plate G to the conveying belts D and D¹, and therefrom through the chute E to the assembling point F. For purposes of clearness, the cover of the chute E is not shown in the drawing. 65 The spacers are stored in the magazine C and are released therefrom by the key lever A¹, after which they pass through the chute or guide C¹ to the assembling point F, and there are composed in line with the type or 70 matrices.

The parts so far described, except as otherwise indicated, are or may be substantially like those disclosed in the previously mentioned Mergenthaler patent. In the 75 present instance, and unlike the machine of the said patent, I employ two converging conveying belts D and D¹, arranged to deliver the type or matrices carried thereby into the common chute E. Also unlike the 80 said patent, the spacer magazine C is shown in a different vertical plane from that of the conveying belts, and it is therefore necessary that either the spacers or the type or matrices be deflected from their normal 85 plane, in order that they may reach the same assembling point. I prefer the latter arrangement, and have therefore mounted the chute E upon the curved plate E¹, which bends outwardly from the plane of the belts 90 D and D¹ into the plane of the spacer chute C¹, thus effecting the delivery of both spacers and type or matrices at the common 95 assembling point F. Because of this form and construction, it will be seen that the spacers will be delivered in a direct vertical 100 line and in the briefest practicable time, thus obviating any liability to their being delayed in transit, and therefore to not being received in the proper and designed relation to the type or matrices.

As the type or matrices are delivered, the composed line is advanced by the longitudinally reciprocated member J, which is pressed rearwardly by spring action, as familiar to those skilled in the art. The member J is not normally connected to its actuating means, which consist of the pawl K, slide K¹, and link or pitman K² eccentrically connected to the constantly rotated 110

disk or wheel K³. The pawl K is formed with an upwardly projecting piece K¹, arranged and located to engage the shoulder J¹ upon the member J. Pivotaly mounted beneath the member J is a trip-lever L, with one end beneath the pawl K and its other end in the path of the descending type or matrices, which are delivered from the chute E. Normally, and when composition is not in progress, the pawl K will be reciprocated without effect upon the member J. When, however, a line is being composed, the type or matrices fall upon the end of the trip-lever L, which is turned about its fulcrum thereby, and raises the pawl K, so that its projection K¹ engages with the shoulder J¹, the result of this temporary connection being to reciprocate the member J through the mechanism already described. It will be seen that in this manner the advancing member is actuated only while type or matrices are being delivered to the line, and that therefore the actuation of the advancing means is controlled by the type or matrices.

Another purpose of my invention is to quicken the delivery of the released type or matrices, and this I preferably accomplish by the employment of a common accelerating device located between the bottom of the magazine and the conveying belts. In the form illustrated, this device is a moving blanket H projecting into the front plate G and mounted upon suitably located rolls H¹ and H², the roll H¹ being preferably rotated by a pulley H³ fast thereon and actuated by the cord or band H⁴, which in turn may receive its motion from any convenient rotated part. As the type or matrices are released from the channeled magazine B in the manner previously described, they are all delivered edgewise onto the moving blanket H, and because of their contact with the latter, their inertia is overcome and they are accelerated in their passage through the front plate to the conveying belts or other assembling means.

As previously stated, my improved devices have been shown in preferred form and by way of example, but obviously many changes and variations therein will suggest themselves to those skilled in the art without departure from the spirit of the invention.

Having thus described my invention, its construction and mode of operation, what I claim and desire to secure by Letters Patent of the United States is as follows:

1. In a linotype machine, the combination of assembling means, a channeled magazine wherein the matrices rest upon their edges, a channeled front plate, releasing means to control the delivery of the matrices from the channels of the magazine to the channels of the front plate, a constantly moving blanket or belt, and supporting rolls therefor so disposed that the stretch or flattened surface of the blanket will lie within the front plate and act upon the edges of the released type or matrices in their passage therethrough to the assembling means.

2. In a linotype machine, the combination of assembling means, a channeled magazine wherein the matrices rest upon their edges, a channeled front-plate, releasing means to control the delivery of the matrices from the channels of the magazine to the channels of the front-plate, and a constantly moving blanket located below the front-plate and onto which the matrices are delivered and whereby they are supported and accelerated in their passage to the assembling means.

3. In a typographical machine, the combination of a line advancing device, constantly operated actuating means therefor and normally disconnected therefrom, and a movable element to effect the connection of said parts, the said element being controlled in its movement by the delivery of the type or matrices.

4. In a typographical machine, the combination of a line advancing device J, its constantly operated actuating member K normally disconnected therefrom but adapted to engage directly therewith, and a movable finger L to effect the engagement of said parts, the said finger being controlled in its movement by the delivery of the type or matrices.

In testimony whereof I hereunto set my hand this first day of June, 1912, in the presence of two attesting witnesses.

JAMES McNAMARA.
